ADJUSTABLE PIANO PEDAL

Henning J. Hansen, Chicago, Ill.

Application September 2, 1954, Serial No. 453,818

1 Claim. (Cl. 84—229)

This invention relates to an adjustable piano pedal and more specifically provides an extension for normal piano pedals thereby permitting children to reach the piano pedals.

An object of this invention is to provide an adjustable piano pedal that permits normal use of the piano pedals by adults and provides an extension for use of the piano pedals by children while practicing or playing.

Another object of the present invention is to provide an adjustable piano pedal for use with a conventional piano wherein children may easily reach the pedals for use thereof.

Yet another important object of the present invention is to provide an adjustable piano pedal that permits children to practice piano with the normal function of the fortissimo and pianissimo pedals thereby permitting the children to learn the function of these pedals.

A still further important object of the present invention is to provide an adjustable piano pedal that is simple in construction, easy to attach, easy to use, well adapted for its intended purposes and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view showing the adjustable piano pedal of the present invention in retracted position for playing of the piano by adults;

Figure 2 is a side elevational view similar to Figure 1 showing the adjustable piano pedals of the present invention in extended position thereby permitting the pedals to be actuated by a child or person with shorter legs;

Figure 3 is a detailed elevational view taken substantially upon reference line 3—3 of Figure 2 showing the positioning of the adjustable piano pedals;

Figure 4 is a detailed sectional view taken substantially upon a plane passing along section line 4—4 of Figure 3 showing the structural details of the adjustable piano pedal and the resilient spring member for retaining the pedal selectively in its extended or retracted position; and

Figure 5 is a detailed sectional view taken substantially along the same plane as Figure 4 and showing the piano pedal of the present invention in retracted position.

Referring now specifically to the drawings, it will be seen that the numeral 10 generally designates the piano pedals of the present invention for use on a conventional piano 12 having a piano bench 14 associated therewith and a keyboard area generally designated by the numeral 16 wherein a person is usually seated on the piano bench 14 for playing the piano and actuating the fortissimo and pianissimo pedals. Each of the pedals 10 generally include an elongated bar 18 pivotally mounted on pivot pin 20 in an aperture 22 extending through the front

2

wall of the piano 12. The bar 18 is pivotally secured to an actuating rod 24 for manipulation of the controls of the piano and the other end of the bar 18 is positioned exteriorly of the front wall of the piano 12.

5 Pivots secured to the outer end of the bar 18 is a channel-shaped member 26 having a closed end portion 28 and a pivot pin 30 extends through the side walls of the channel member 26 and through the end of the bar 18 thereby pivotally securing the channel member 26 to the bar 18. The other end of the channel member 26 is provided with a generally rounded projection 32 that extends at right angles to the web portion of the channel-shaped member 26. Secured within the channel-shaped member 26 is a generally bowed flat spring 34 secured adjacent the open end thereof by a screw member 36. The free end of the resilient member 34 engages the flat end portion 38 of the bar 18 when the channel-shaped member 26 and the bar 18 are positioned in substantially perpendicular position. When the channel-shaped member 26 is moved to a position adjacent the upper edge of the bar, the spring 34 engages the flat upper edge of the bar 18 thereby urging the channel-shaped member 26 and the projection 32 to the retracted position substantially as shown in Figure 5.

20 As shown in Figures 1 and 5, the channel-shaped member 26 and the projection 32 are in retracted position with the channel-shaped member engaging the upper surface of the bar 18 wherein the pedal will be formed by the bight portion of the channel-shaped member 26 and the upward projection 32 will provide a limit means for the positioning of a person's foot thereon. When the channel-shaped member 26 is moved to an extended position, the spring 34 engages the outer flat end 38 of the rod 18 and retains the channel-shaped member 26 in perpendicular relation thereto. The forwardly extending projection 32 then forms a pedal on its upper surface for engagement by a child's foot thereby permitting actuation of the bar 18 and the control rod 24 by small children during practice on the piano 12.

25 40 The device may be constructed of suitable brass and shaped in any suitable manner wherein the usual piano pedals will be provided with an extension device for permitting access to the pedals by children.

45 From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claim.

50 55 What is claimed as new is as follows:

An adjustable piano pedal comprising an elongated bar pivotally mounted on and extending through the front wall of a piano, said bar having a free end projecting horizontally outwardly from the front wall of a piano with the other free end extending inwardly of the front wall for connection to a control rod, a channel-shaped member having a closed end and an open end, a transverse pivot pin extending through the legs of the channel-shaped member and the bar adjacent the free end of the bar and the closed end of the channel-shaped member with the legs of the channel-shaped member straddling the bar, said channel-shaped member being normally disposed in horizontal position with the web thereof overlying a portion of the bar and forming a foot-engaging surface for operating the bar, a bowed flat spring mounted on the inner surface of the web of the channel-shaped member adjacent the free end thereof for engaging the flat upper surface of the bar adjacent the pivot pin for

releasably retaining the channel-shaped member in horizontal relation, a projection extending perpendicularly outwardly from the free end of the outer surface of the web of the channel-shaped member, said projection being disposed remote from the transverse pin for positioning a person's foot on the outer surface of the channel-shaped member, said free end of the bar terminating in a flat vertical surface having a rounded corner with the flat surface engaging the inner surface of the closed end of the channel-shaped member, said channel-shaped member being pivotal about the transverse pin to a verti-

cal position with the upper surface of the projection being horizontally disposed to form a foot-engaging surface spaced vertically above the bar, said flat spring engaging the flat end of the bar when the channel-shaped member is in vertical position thereby releasably retaining the channel-shaped member in vertical position.
